UNITED STATES PATENT OFFICE.

GRANT M. SIMON, OF PHILADELPHIA, PENNSYLVANIA.

BUILDING-BLOCK.

1,291,205.

Specification of Letters Patent. Patented Jan. 14, 1919.

Application filed April 18, 1916. Serial No. 91,872.

To all whom it may concern:

Be it known that I, GRANT M. SIMON, a citizen of the United States, residing at Philadelphia, in the county of Philadelphia and State of Pennsylvania, have invented 5 certain new and useful Improvements in Building-Blocks, of which the following is a specification.

This invention relates to building blocks 10 and particularly to building blocks having overlapping portions.

Among the objects of my invention is to provide building elements with offset portions, adapted to coöperate in forming a wall 15 or other structure, with channels or air spaces between said elements, running both vertically and horizontally, said vertical channels communicating with said horizontal channels.

20 The invention consists in the peculiar form given to the block.

Referring to the drawings, which represent, merely by way of example, suitable embodiments of my invention, Figure 1 is a 25 perspective view of my block in the form of a hollow tile; Fig. 2 is a plan of the block; Fig. 3 is a vertical section of the block taken on the line 3—3 of Fig. 2. Fig. 4 is a perspective view of a modified form of a hollow 30 tile block embodying my invention. Fig. 5 is a plan of the same; Fig. 6 is a vertical section of such a block, taken on the line 6—6 of Fig. 4. Fig. 7 is a view of a further modified form, embodying my invention in a solid 35 block; Fig. 8 is a plan of the same; Fig. 9 is a vertical section of the same taken along the line 9—9 of Figs. 7 and 8.

Similar numerals refer throughout to similar parts.

40 Referring now more specifically to the annexed drawings, the hollow building block, illustrated by Fig. 1, comprises two quadrangular sections, A and B, each hollow vertically. These two sections are maintained 45 in parallel spaced relation to one another by vertical transverse webs 14, 15 and 16. Sections A and B are offset with relation to one another horizontally, so that one end of section A extends beyond web 15 and the end of section B, so as to form a hollow shoulder or extension 17; and so that, similarly, the opposite end of section B extends beyond the web 14 and the end of section A, so as to form a hollow shoulder or extension 17'. 55 Sections A and B are offset in a vertical direction so that section B extends above sec-

tion A and the connecting webs 14, 15 and 16; and so that section A extends below section B and the said connecting webs.

When the sections A and B of such building blocks are given equal dimensions, the blocks are symmetrical and will fit to each other when placed adjacent to one another in the same course or in different courses.

When placed adjacent in the same course, 60 the shoulder 17 will overlap the shoulder 17' of the block alongside. The joint between the two will be broken and within the broken joint will be left the vertical hollow space 18, continuous with the vertical hollow spaces 70 directly above and below, and, therefore, continuous throughout the height of the wall.

When the blocks are placed upon one another in different courses, section A of the 75 block above will overlap section B of the block beneath. The horizontal joint between the two will be broken and within the joint will be left the horizontal hollow space 19. It is apparent that this horizontal hollow 80 space runs the length of the course without interruption and that it communicates with the vertical air spaces formed by the webs 14, 15 and 16, and through these to the other horizontal air spaces within the horizontal 85 joints of the courses above and below. In this way I attain an almost perfectly dry and non-conducting wall.

Section A presents the outer or exposed 90 face of the block and may, therefore, be finished as desired. The ends of the block receive mortar and they may be conveniently corrugated, as illustrated. The rear face of the block, that is of section B, may also be conveniently corrugated, so that it may receive directly a layer of plaster, cement or 95 mortar, etc.

The vertical hollow space within the 100 broken vertical joints between blocks in the same course, I show plainly at 18 of Fig. 2; the horizontal air space within the broken horizontal joints between courses, I show plainly at 19 of Fig. 3.

My block, in the modified form illustrated by Fig. 4, consists of a single hollow section, 105 composed of the front and back webs 21 and 21', the end webs 22 and 22', and, to strengthen the block, one or more vertical webs 20, dividing the block transversely. The two sides 21 and 21' are offset with relation to one another both horizontally and 110 vertically, so that one end of the side 21 ex-

tends beyond the end web 22', to form a flange or shoulder 23; and in like manner the opposite end of side 21' extends beyond the end web 22, to form a vertical flange or shoulder 23'.

The sides 21 and 21' are vertically offset with relation to one another, so that side 21' extends above the block to form a horizontal flange or shoulder 24. In like manner the side 21 extends below the block to form the horizontal flange or shoulder 24'.

When symmetrical blocks of this kind are placed adjacent to one another in the same course, the shoulder 23 overlaps the shoulder 23' of the block alongside, leaving within this broken joint the vertical air space 25 (Fig. 5).

When placed upon one another in different courses, the horizontal shoulder 24' of side 21 will overlap the horizontal shoulder 24 of side 21' of the block beneath, leaving within this broken joint the horizontal air space 26 (Fig. 6). It is apparent that this horizontal air space runs uninterruptedly the length of the course and that it communicates with the vertical air spaces within the block and within the vertical joints, and through these to the horizontal air spaces between other courses.

It is apparent, in the blocks so far described, that neither the dimensions of the block, nor of the vertical or horizontal shoulders, nor the arrangement of the interior webs, relate in any way to the essential feature of my invention. Furthermore, such blocks may be molded of solid concrete or other material without affecting the essential idea of my invention, which it is my intention to claim in all such modified forms.

My block may be made solid instead of hollow without in any way affecting the novel features of my invention. Such form I illustrate in Figs. 7, 8 and 9. In this form the block consists of the body C. The back face projects above C so as to form the shoulder 27, in width less than one-half the width of the block. The front face projects below C so as to form the shoulder 28, in width less than one-half the width of the block. The

back face 27 also projects beyond one end of the block C so as to form the shoulder 29, of equal width with the shoulder 27. The front face projects beyond the opposite end of the body C so as to form the shoulder 30, of equal width with the shoulder 28.

When blocks of this form are placed in co-operative relation, the shoulders 28 rest upon the bodies C of the blocks in the course immediately beneath, and the bodies C of the upper course rest upon the shoulders 27 of the blocks immediately beneath. Thus the bodies C are kept apart and an air space 31 is formed within the joint. The shoulders 29 and 30 form a vertical air space 32 in the vertical joint. Throughout the wall 65 the longitudinal air spaces 31 communicate with the vertical air spaces 32.

Having thus described my invention, what I claim as new and desire to secure by Letters Patent is:—

A wall constructed of blocks, the blocks provided with longitudinal shoulders in thickness less than one-half the width of the block, the said shoulders projecting the one above, the other below the block and flush with the rear and front faces respectively; and provided with vertical shoulders in thickness less than one-half the width of the block, the said shoulders flush with the front and rear faces projecting from opposite ends thereof; said blocks being laid adjacent to one another, the end vertical shoulder of each block overlapping the end vertical shoulder of the block next to it in the same course, the upper and rear longitudinal shoulder overlapping the lower and front longitudinal shoulder of the block in the course immediately above it; the hollow spaces left in the vertical joints opening into the hollow spaces left in the longitudinal joints above and below.

In testimony whereof, I do affix my signature in the presence of two witnesses.

GRANT M. SIMON.
